CLAIM

The ornamental design for a printing device with flatbed scanner, as shown and described.

DESCRIPTION

FIG. 1 is a perspective view of a printing device having a flatbed scanner.

FIG. 2 is a top view of the printing device of FIG. 1.

FIG. 3 is a right side view of the printing device of FIG. 1.

FIG. 4 is a left side view of the printing device of FIG. 1.

FIG. 5 is a front view of the printing device of FIG. 1.

FIG. 6 is a back view of the printing device of FIG. 1.

FIG. 7 is a perspective view of the printing device of FIG. 1 in which the output tray has been extended and the scanner lid has been raised.

FIG. 8 is a top view of the printing device of FIG. 1 in which the output tray has been extended and the scanner lid has been raised.

FIG. 9 is a right side view of the printing device of FIG. 1 in which the output tray has been extended and the scanner lid has been raised.

FIG. 10 is a left side view of the printing device of FIG. 1 in which the output tray has been extended and the scanner lid has been raised.

FIG. 11 is a front view of the printing device of FIG. 1 in which the output tray has been extended and the scanner lid has been raised; and,

FIG. 12 is a back view of the printing device of FIG. 1 in which the output tray has been extended and the scanner lid has been raised.

Any portions shown in broken lines in the figure are for illustrative purposes only and form no part of the claimed design.
